United States Patent Office

Des. 211,833
Patented July 30, 1968

211,833

SLIDE VIEWER OR SIMILAR ARTICLE

Eugene Martinez and Sebastian Matilla, Irvington, N.Y., assignors to Hudson Photographic Industries Inc., Irvington, N.Y., a corporation of New York

Filed Feb. 10, 1966, Ser. No. 1,059

Term of patent 14 years

(Cl. D61—1)

FIG. 1

FIG. 2

FIG. 1 is a top front perspective view of a slide viewer or similar article showing our new design with a conventional slide being shown in broken lines for illustrative purposes; and

FIG. 2 is a bottom rear perspective view thereof.

We claim:

The ornamental design for a slide viewer or similar article, substantially as shown and described.
